(57) **ABSTRACT**

Apparatus is provided for training people in technique and tactics for use in wrestling and other combat sports. The apparatus presented comprises a rigid and elastic frame, padding, low-friction feet or runners, and a platform for another user or weights, to add mass and resistance for the user training with the apparatus. A user may use the apparatus to practice penetration techniques, agility, and strength while training in free motion. The apparatus leads the user to use her or his body weight, the weight of the apparatus, and optionally added weight, in training while on matted surfaces, providing a better training experience and practice than prior art training devices. The present invention solves problems with the currently available means and apparatuses of practicing penetration techniques and tactics.

TRAINING APPARATUS FOR COMBAT SPORTS

FIELD OF THE INVENTION

The presently disclosed subject matter relates to providing apparatus for training in wrestling and other combat sports, and more particularly, to apparatus for practicing penetration techniques and tactics.

BACKGROUND OF THE INVENTION

In training for wrestling and other combat sports and disciplines, including but not limited to mixed martial arts, capoeira, and Brazilian jiu-jitsu, a person must learn and practice what are referred to as penetration techniques and tactics. Penetration, in this context, refers to the act and process of stepping into one's opponent, by stepping forward with one foot and moving one's hips forward. There are multiple tactics by which one can penetrate into an opponent. Existing apparatus and training devices allow a user to practice grappling and improve necessary strength, but do not allow a user to practice penetration techniques while in free motion across a matted surface, meaning a surface covered with padded mats such as those on which wrestling practice and matches take place. To develop and practice the penetration techniques, a person must be able to freely move around on the matted surface, so that the person can practice stepping forward into the opponent and moving one's hips forward to drive the opponent backward, while grappling with the opponent. Prior art devices, such as U.S. Pat. No. 3,888,481 to Adams, Jr. et al. (the '481 patent) and US Patent Application 2006/0116250 by Adams and Walker, Jr. (the '250 application), allow a user to grapple with a dummy figure of a person, which dummy is mounted on springs attached to a framework, but which framework is not safely moveable across a matted surface. Neither the '481 patent nor the '250 application allow a user to practice penetration techniques while in free motion across a matted surface, limiting their usefulness in training for wrestlers and other combat sport trainees. Non-patented products exist as well, such as the "attacker dummy" and "snap and shoot plus" disclosed in the Information Disclosure Statement by Applicant filed with this application, and which examples contain the same shortcomings as patent-literature prior art: the "snap and shoot plus" and similar products are bolted to a wall, precluding practice in free motion across a surface, among other shortcomings; and the "attacker dummy" cannot be a stable object that a practitioner could use to practice shooting and other penetration techniques while driving an opponent backwards across a surface.

Other devices exist for training users in grappling and movement in other contexts, such as in blocking in football. A football blocking sled does allow a user to train in grabbing another person and pushing them, but this is not the same as penetration techniques and tactics. A football blocking sled, such as US Patent Application 2010/0203986 by Gilman (the '986 application), presents a blocking-practice apparatus that may be loaded with weights to provide varying amounts of resistance, and which may be used on a playing-field surface, such as grass, dirt, or artificial turf. But the '986 application does not allow for use on a matted surface, which it would tear up and destroy. It also is not useable for practicing penetration techniques because the geometry of the uprights is conducive to practicing grabbing an opponent by the torso or arms, but not practicing grabbing an opponent by the waist or legs, as the uprights are too

far apart from each other. Furthermore, the arrangement of the components comprising the '986 application are conducive to training a user to grapple with an opponent and pushing into them with the user's torso and midsection while driving with the user's legs behind the user. In contrast, when practicing penetration techniques, the user must practice driving into the opponent's midsection and getting the user's center of gravity low so as to drive one of the user's legs between the opponent's legs—which is referred to as "shooting"—in order to take down the opponent—meaning drag them down onto the matted surface to pin them. The '986 application, and other prior art aimed at practicing football blocking (or other blocking for field sports), cannot allow a user to practice shooting, because there either is not space for the user's leg to go between the uprights, or there is a cross brace situated so close to the uprights that the user would damage his or her leg in the process.

Finally, the prior art does not allow a user to practice penetration techniques in free motion on a mat, solo. Practice against other people is typically useful, but at times, it is helpful for the person practicing and for others, such as a coach, to be able to practice alone, to focus on their own techniques. The present invention allows a user to practice penetration techniques and tactics alone, and also with a partner as weight on the apparatus. In summary, the problems of the prior art are a lack of suitable apparatus for practicing penetration techniques, for practicing solo, for practicing penetration techniques in free motion, and for practicing on matted surfaces.

SUMMARY OF THE INVENTION

The present invention meets all these needs, by disclosing apparatus that allows a user to practice penetration techniques and tactics on matted surfaces without damaging the surface; that allow a user to fully practice penetration techniques without injuring themselves; that allow a user to practice while in free motion, as opposed to constrained to one place; and that allow a user to practice solo. The present invention relates broadly to apparatus for practicing techniques used in wrestling and combat sports, and more particularly to apparatus for practicing grappling and penetration techniques and tactics. The goals of the present invention are to allow a user to practice relevant penetration techniques in training on wrestling or similar mats. The present invention further addresses the problem of other apparatus that constrain the user to one place while practicing techniques, whereas in a match setting the user needs to be in motion across the mats.

The present invention addresses the problems of the prior art, which do not present apparatus for training that allow practice of penetration techniques and tactics on matted surfaces without damaging the surface and without injuring the user, and that allow a user to practice while in free motion. The present invention meets these needs.

Further, the present invention introduces a product that allows a user to practice solo, improving the opportunities for practice, as a suitable wrestling opponent is not always available in practice, and improving the ability of others to observe and coach a user, as the only variable is the user's technique, not the actions of an opponent, so a coach and the user can focus on the user's own technique.

These aspects of the present invention, and others disclosed in the Detailed Description of the Drawings, represent improvements on the current art. This summary is provided to introduce a selection of concepts in a simplified form that are further described below in the Detailed

Description of the Drawings. This Summary is not intended to identify key features or essential features of the claimed subject matter, nor is it intended to be used to limit the scope of the claimed subject matter.

BRIEF DESCRIPTION OF THE DRAWINGS

The foregoing summary, as well as the following detailed description of various aspects, is better understood when read in conjunction with the appended drawings. For the purposes of illustration, the drawings show exemplary aspects; but the presently disclosed subject matter is not limited to the specific methods and instrumentalities disclosed. In the drawings, like reference characters generally refer to the same components or steps of the device throughout the different figures. In the following detailed description, various aspects of the present invention are described with reference to the following drawings, in which:

FIG. 1 shows a front and top perspective view of an aspect of the apparatus of the present invention.

FIG. 2 shows a front elevation view of an aspect of the apparatus of the present invention.

FIG. 3 shows a side elevation view of an aspect of the apparatus of the present invention.

FIG. 4 shows a top elevation view of an aspect of the apparatus of the present invention.

FIG. 5 shows a perspective view of an aspect of the apparatus of the present invention, from the top and rear, with a user of the apparatus depicted as interacting with the apparatus at the front of the apparatus.

FIG. 6 shows a front and top perspective view of an aspect of the apparatus of the present invention.

FIG. 7 shows a top elevation view of an aspect of the apparatus of the present invention.

FIG. 8 shows a front and top perspective view of an aspect of the apparatus of the present invention.

FIG. 9 shows a front elevation view of an aspect of the apparatus of the present invention.

FIG. 10 shows a top elevation view of an aspect of the apparatus of the present invention.

FIG. 11 shows an exploded side elevation view of an aspect of the apparatus of the present invention.

DETAILED DESCRIPTION OF THE DRAWINGS

The presently disclosed invention is described with specificity to meet statutory requirements. But, the description itself is not intended to limit the scope of this patent. Rather, the claimed invention might also be embodied in other ways, to include different steps or elements similar to the ones described in this document, in conjunction with other present or future technologies. Moreover, although the term "step" or similar terms may be used herein to connote different aspects of methods employed, the term should not be interpreted as implying any particular order among or between various steps herein disclosed unless and except when the order of individual steps is explicitly described. The word "approximately" as used herein means within 5% of a stated value, and for ranges as given, applies to both the start and end of the range of values given.

In the following description, numerous specific details are set forth to provide a thorough understanding of the invention. But, the present invention may be practiced without these specific details. Structures and techniques that would be known to one of ordinary skill in the art have not been shown in detail, in order not to obscure the invention.

Referring to the figures, it is possible to see the various elements constituting the apparatus and methods of use the present invention.

The present invention comprises a novel apparatus 100 for practicing techniques and tactics for combat sports, including but not limited to wrestling, mixed martial arts, capoeira, and Brazilian jiu-jitsu.

With reference to FIGS. 1, 2, 3, and 4, the apparatus 100 of the present invention comprises a grappling upright 110, a first horizontal tube 130, a second horizontal tube 132, a first horizontal brace 134, a plurality of horizontal brace supports 135, a plurality of upright-horizontal braces 138, a first horizontal runner 150, and a second horizontal runner 152. The grappling upright 110 further comprises an upright first side 112 and an upright second side 114, which, it has been found advantageous, are formed or joined to each other with a grappling top angle 116 between the upright first side 112 and the upright second side 114. The grappling top angle 116, it has been found advantageous, in one aspect of the present invention, may be approximately 160° to 162°, for reasons described below. In another aspect of the present invention, the grappling top angle 116 may be approximately 150° to 170°. It will be understood by one of skill in the art that other grappling top angle 116 dimensions are possible. In one aspect of the present invention, the upright first side 112 and the upright second side 114 are then straight for approximately 36". In another aspect, the upright first side 112 and the upright second side 114 are then straight for approximately 30" to 42".

The grappling upright 110 further comprises a grappling first side vertical section 118 which in one aspect of the present invention is at a grappling lower angle 128 of approximately 9°-10° relative to the upright first side 112; and a grappling second side vertical section 120 which is at a grappling lower angle 128 of approximately 9°-10° relative to the upright second side 114. In another aspect of the present invention, the vertical section 118 which is at a grappling lower angle 128 of approximately 0°-15° relative to the upright first side 112; and a grappling second side vertical section 120 which is at a grappling lower angle 128 of approximately 0°-15° relative to the upright second side 114. It will be understood by one of skill in the art that other dimensions are possible. The upright first side 112 and the upright second side 114 and the grappling first side vertical section 118 and the grappling second side vertical section 120 may, it has been found advantageous, be formed from a single tube or other piece of metal or other suitable material, or may be formed from separate pieces of material. Together, comprising the grappling upright 110, the upright first side 112, the upright second side 114, the grappling first side vertical section 118, and the grappling second side vertical section 120 may, it has been found advantageous, turn through approximately 160°-180° of turns (the grappling lower angle 128 plus the grappling top angle 116 plus the grappling lower angle 128), such that in one aspect of the present invention the grappling first side vertical section 118 and the grappling second side vertical section 120 are both approximately vertical and parallel to each other, and are each, it has been found advantageous, approximately 6" to 8" long. In another aspect of the present invention, the grappling first side vertical section 118 and the grappling second side vertical section 120 are both approximately 4" to 10" long. It will be understood by one of skill in the art that other first side vertical section 118 and the grappling second side vertical section 120 lengths are possible. Below the grappling first side vertical section 118 and the grappling second side vertical section 120 are, on each side, a grap-

pling upright—horizontal tube joint 122, which may be a bend in the single piece of material comprising the grappling upright 110, or may be a joint between separate pieces of material. In another aspect of the present invention, the grappling first side vertical section 118 and the grappling second side vertical section 120 may not be vertical, and may be in line with or a continuous portion of the upright first side 112 and the upright second side 114, respectively, such that the grappling first side vertical section 118 and the grappling second side vertical section 120 are connected to the grappling upright—horizontal tube joint 122 at an angle relative to a hypothetical vertical or plumb line.

In one aspect of the present invention, the overall height of the grappling upright 110, from the bottoms of the grappling first side vertical section 118 and the grappling second side vertical section 120, through the upright first side 112 and the upright second side 114, to the top of the material of the grappling upright 110 at the top of the grappling top angle 116, is advantageously approximately 48". In another aspect of the invention, the overall height is approximately 36" to 60" for reasons that are discussed below.

The sides of the grappling upright 110 are advantageously covered with a first upright pad 124 and a second upright pad 126, which may cover most or all of the upright first side 112, the upright second side 114, the grappling first side vertical section 118, and the grappling second side vertical section 120. The first upright pad 124 and the second upright pad 126 are advantageously be of a material or materials which provide sufficient padding to allow a user 210 to grapple and shove hard against the grappling upright 110 without undue injury to the user 210.

With further reference to FIG. 6, FIG. 7, FIG. 8, FIG. 9, FIG. 10, and FIG. 11, below the grappling upright 110, and approximately perpendicular to the grappling upright 110, are the first horizontal tube 130 and the second horizontal tube 132 which comprise a floor piece 188. The first horizontal tube 130 and the second horizontal tube 132 may, it has been found advantageous, be formed from a single piece of material continuous with the grappling upright 110; or the grappling upright 110 may be joined to the first horizontal tube 130 and the second horizontal tube 132 at the grappling upright—horizontal tube joints 122. In other aspects of the present invention, and with reference to FIG. 6, FIG. 7, FIG. 8, FIG. 9, and FIG. 10, below the grappling upright 110, and approximately perpendicular to the grappling upright 110, is a floor piece 188 which may be a continuous solid sheet or may be a perforated piece or pieces of material, in any shape. The floor piece 188 may comprise outside edges, namely the portions of the floor piece 188 laterally farthest from the center of the floor piece 188 and not at the front or back of the apparatus 100. The floor piece 188 may comprise the first horizontal tube 130 and the second horizontal tube 132 as some portions of the floor piece 188, or in other aspects of the present invention, the floor piece 188 may be the underside support of the apparatus 100, without any first horizontal tube 130 or any second horizontal tube 132. In one aspect of the invention, the grappling upright 110 may be reversibly attached to and detached from the lower portions of the apparatus, whether those lower portions comprise the floor piece 188, or the first horizontal tube 130 and the second horizontal tube 132, through an interlocking mechanism 186, which interlocking mechanism 186 may be any connection elements or attachment elements now known or later invented. In one aspect of the invention, the floor piece 188 may be covered or partially covered, on its underside (the side in contact with

the floor or mat) with a floor sheet 182 of, advantageously, low friction material; which floor sheet 182 is disposed to allow the apparatus 100 to slide across the floor or mat. In another aspect of the present invention, the floor sheet 182 may be significantly smaller in area than the overall horizontal footprint (the front-back and side-side extent) of the apparatus 100. In some aspects of the present invention, the floor piece 188 may cover less than the entire footprint of the apparatus 100, and/or the floor sheet 182 may cover or extend over only a portion of the footprint of the apparatus 100. In all aspects of the present invention, the materials used for the grappling upright 110 and the floor piece 188 may, it has been found advantageous, be sufficiently strong and elastic that they can endure energetic use and impacts which are typical in training for wrestling and other combat sports. The material used for the grappling upright 110 may, it has been found advantageous, be of sufficient diameter (or cross-sectional size, if not circular) that it is comfortable for a typical range of users to grapple with when the material is wrapped in padding, such as the first upright pad 124 and the second upright pad 126, and that it is strong and elastic to endure energetic use and impacts which are typical in training for wrestling and other combat sports. One such suitable material is steel tubing of approximately 1.5" outer diameter, though other materials and cross-sectional sizes and cross-sectional shapes are possible, including but not limited to aluminum, graphite, and materials now known or later invented. The grappling upright 110 may be braced to the first horizontal tube 130 and the second horizontal tube 132 with one or more upright-horizontal braces 138, advantageously with an upright-horizontal brace 138 on each side of the grappling upright 110.

In some aspects of the present invention, the first horizontal tube 130 and the second horizontal tube 132 may, it has been found advantageous, each comprise a horizontal tube lateral bend 160, at which the first horizontal tube 130 turns laterally to the left, away from the center of the apparatus 100, and the second horizontal tube 132 turns laterally to the right, away from the center of the apparatus 100. In another aspect of the invention, with reference to FIG. 6, FIG. 7, FIG. 8, FIG. 9, and FIG. 10, where the floor piece 188 is a continuous solid sheet or perforated piece or pieces of material, the floor piece may comprises one or more horizontal lateral bends 161, which widen the floor piece 188 in the aspect of it farther from the grappling upright 110. The goals of the horizontal tube lateral bends 160 or of the horizontal lateral bends 161 are to increase the lateral stability of the apparatus 100, by providing a wider base (the footprint of the first horizontal tube 130 and the second horizontal tube 132, as seen in FIG. 4, or the footprint of the floor piece 188) that resists tipping of the apparatus 100. The horizontal tube lateral bends 160 may be located on the first horizontal tube 130 and the second horizontal tube 132 forward (closer to the grappling upright 110) of the first horizontal brace 134, as shown in FIGS. 1, 3, and 4; in aspects of the present invention with a floor piece, the horizontal lateral bends 161 may likewise be located forward (closer to the grappling upright 110) of the first horizontal brace 134.

In some aspects of the present invention, the first horizontal tube 130 and the second horizontal tube 132 may, it has been found advantageous, each have an upright bend 162, at which the first horizontal tube 130 turns vertically up, away from the mat, and the second horizontal tube 132 turns vertically up, away from the mat, as shown in FIG. 3. In another aspect of the invention, with reference to FIG. 6, FIG. 7, FIG. 8, FIG. 9, and FIG. 10, where the floor piece

188 is a continuous solid sheet, or one or more pieces of material, it may have an upright bend 162 away from the mat, or in aspects of the present invention where the floor piece 188 comprises separate pieces at the back (away from the user 210 and the grappling upright 110), each such piece or portion of the floor piece 188 may have an upright bend 162. The goals of the upright bend 162 or upright bends 162 are to allow the apparatus 100 to tip backwards as the user 210 drives into it, and to be moved backwards while the user 210 drives into the apparatus 100, without having the edges or ends of the first horizontal runner 150 and the second horizontal runner 152 impact the mat, which could result in damage to the mat. If the user's 210 practice of technique with the apparatus 100 tips the apparatus backwards (moving the top of the grappling upright 110 away from the user 210 and closer to the mat), the upturned ends of the first horizontal runner 150 and the second horizontal runner 152 allow the apparatus 100 to be driven backwards without digging into the mat. The horizontal tube upright bends 162 are advantageously placed near the back ends (the ends away from the grappling upright 110) of the first horizontal tube 130 and the second horizontal tube 132, as shown in FIG. 3. Likewise, in aspects of the present invention with a floor piece 188 without a first horizontal tube 130 or a second horizontal tube 132, the upright bends 162 are advantageously placed near the back end or ends of the floor piece 188. In aspects of the present invention with upright bends 162, the floor piece 188 and/or first horizontal tube 130 and a second horizontal tube 132 may appear to be shaped like water skis or snow skis, with the upright bends 162 curved gradually, that is like a curve with a radius of approximately 2" to approximately 20", as opposed to an angled and abrupt bend in the relevant material.

With reference to FIGS. 1, 2, and 3, the apparatus 100 further comprises a first horizontal runner 150 and a second horizontal runner 152. The first horizontal runner 150 is attached to and underneath the first horizontal tube 130, and the second horizontal runner 152 is attached to and underneath the second horizontal tube 132. The first horizontal runner 150 and the second horizontal runner 152 are, it has been found advantageous, made of or coated with a low-friction material so that the first horizontal runner 150 and the second horizontal runner 152 do not tear up or damage the padded wrestling mats on which the apparatus 100 is intended to be used in training for combat sports. In some aspects of the present invention, the first horizontal runner 150 and the second horizontal runner 152 may be coatings applied to an underside (namely, the side or surface which is closest to the mat or floor when the apparatus 100 is in use) of the first horizontal tube 130 and of the second horizontal tube 132. In other aspects of the invention, as pictured in FIG. 3 and FIGS. 1, 2, 4, and 5, the first horizontal runner 150 and the second horizontal runner 152 may be separate pieces from the first horizontal tube 130 and the second horizontal tube 132, and may be attached to the first horizontal tube 130 and the second horizontal tube 132 with a plurality of first horizontal runner supports 140 (attaching the first horizontal runner 150 to the first horizontal tube 130) and a plurality of second horizontal runner supports 142 (attaching the second horizontal runner 152 to the second horizontal tube 132). The plurality of first horizontal runner supports 140 and the plurality of second horizontal runner supports 142 may space the first horizontal tube 130 and the second horizontal tube 132 away from the mats, above the first horizontal runner 150 and the second horizontal runner 152. Alternatively, the plurality of first horizontal runner supports 140 and the plurality of second

horizontal runner supports 142 may snugly join the first horizontal tube 130 and the second horizontal tube 132 to the first horizontal runner 150 and the second horizontal runner 152. The goal of the first horizontal runner 150 and the second horizontal runner 152, in the present invention, is to provide a low-friction area of contact between the apparatus 100 and the mats, so that when a user 210 is grappling with the apparatus 100, the apparatus 100 can slide across the mats without damaging the mats. In other aspects of the present invention, wherein there is a floor piece 188 and not a first horizontal tube 130 and a second horizontal tube 132, the underside of the floor piece 188 may be covered in part or in whole with any suitable low-friction material, to serve the same goals as set forth herein as any first horizontal runner 150 and any second horizontal runner 152; such low-friction material comprising elements of the present invention referred to as the floor sheet 182.

The front of the apparatus 100, namely the face of the grappling upright 110 with which the user 210 grapples with the user's torso, as shown in FIG. 5, is distant from the front of the first horizontal brace 134 (namely, the edge or side of the first horizontal brace 134 that is closest to the grappling upright 110) by a distance referred to as a first horizontal brace setback 136, as marked in FIGS. 1, 3, and 4. In one aspect of the invention, the first horizontal brace setback 136 is approximately 16", to allow the user 210 to shoot a knee and leg between the upright first side 112 and the upright second side 114 of the grappling upright 110, to practice shooting and penetration techniques, without impacting the knee or leg of the user 210 on the first horizontal brace 134. In another aspect of the invention, the first horizontal brace setback 136 is approximately 8" to 24". It will be understood by one of skill in the art that other dimensions of the first horizontal brace setback 136 are possible, so as to allow a shorter or a taller user 210 of the apparatus 100 to practice penetration techniques without injury. The goals of the first horizontal brace 134 are two-fold: first, to provide lateral stability to the apparatus 100, by bracing the first horizontal tube 130 to the second horizontal tube 132, reducing lateral flexion and twisting of the first horizontal tube 130 and the second horizontal tube 132 relative to each other; and second, to allow additional mass to be added to the apparatus 100 for training the user 210, for which the first horizontal brace 134 may, it has been found advantageous, be able to support additional mass. The additional mass may be a second person (other than the user 210) also referred to as an assistant-user, standing on the first horizontal brace 134 or on a plurality of assistant-user-footblocks 189, or the additional mass may be weights or other objects. With reference to FIG. 3, FIG. 4, FIG. 6, FIG. 7, and FIG. 9, the plurality of assistant-user-footblocks 189 may be formed on or attached to the floor piece 188. In some aspects of the present invention, it may be advantageous to have exactly two such footblocks in the plurality of assistant-user-footblocks 189; in other aspects of the present invention, there may be more assistant-user-footblocks 189, which may be disposed at any of a range of angles relative to the floor piece 188, or be adjustable; and which plurality of assistant-user-footblocks 189 may be of a range of sizes to accommodate a range assistant-users. By adding mass to the apparatus, a user 210 can practice penetration and driving into an opponent of varying mass, which is necessary for training and development, and is one of the unmet needs of the prior art. The first horizontal brace 134 may be attached to the first horizontal tube 130 and the second horizontal tube 132 with a plurality of horizontal brace supports 135, or may be attached directly to the first horizontal tube 130 and the

second horizontal tube 132. One advantage of using a plurality of horizontal brace supports 135 is that it raises the center of mass of the apparatus 100 and especially so with weights added to the first horizontal brace 134, more accurately simulating the height of the center of mass of an opponent.

With reference to FIGS. 1, 2, and 4, the apparatus 100 comprises an internal horizontal span 170 between the grappling first side vertical section 118 and the grappling second side vertical section 120. In one aspect of the present invention, the internal horizontal span 170 may be, advantageously, approximately 14", to allow the user 210 sufficient lateral space to shoot in either knee and leg from a variety of body positions when grappling with the grappling upright 110, "shoot in" meaning, for the avoidance of doubt, insert a knee between, on the left, the upright first side 112 and the grappling first side vertical section 118, and on the right, the upright second side 114 and the grappling second side vertical section 120. In another aspect of the invention, the internal horizontal span 170 may be approximately 8" to 24". It will be understood by one of skill in the art that other dimensions of the internal horizontal span 170 are possible. There is horizontal space between the upright first side 112 and the upright second side 114, which tapers down the higher up inside of the grappling upright 110 one measures.

The apparatus 100 further comprises, with reference to FIGS. 1 and 2, an internal vertical span 172, which is the distance from the undersides of the first horizontal runner 150 and the second horizontal runner 152 (where the first horizontal runner 150 and the second horizontal runner 152 contact the mats or other floor) to the underside of the grappling upright 110 at its highest region, the grappling top angle 116. The goal of the internal vertical span 172 is to allow users 210 of varying heights space to practice penetration by driving a portion of the user's 210 torso, shoulder, knee, and/or hips into the space between the upright first side 112 and the upright second side 114, while driving forward into the grappling upright 110 and attempting to move the apparatus 100 backwards. In one aspect of the present invention, the internal vertical span 172 may, it has been found advantageous, be approximately 48". In another aspect, the internal vertical span 172 may, it has been found advantageous, be approximately 36" to 60", though it will be understood by one of skill in the art that other dimensions of the apparatus 100 and thus the internal vertical span 172 are possible.

With reference to FIG. 5, to use the apparatus 100, the apparatus 100 may be placed on mats or other flooring, and a user 210 may grapple with the apparatus 100. In this way, the user 210 may grab the grappling upright 110 with the one or both of the user's 210 hands, while driving the user's 210 shoulder, knee, or hips into or towards the grappling upright 110. The user may also practice shooting a knee into the space between, on the user's 210 left, the upright first side 112 and the grappling first side vertical section 118, and on the right, the upright second side 114 and the grappling second side vertical section 120.

Certain aspects of the present invention were described above. From the foregoing it will be seen that this invention is one well adapted to attain the ends and objects set forth above, together with other advantages, which are apparent in and inherent to the inventive apparatus disclosed herein. It will be understood that certain features and sub-combinations are of utility and may be employed without reference to other features and sub-combinations. It is expressly noted that the present invention is not limited to those aspects described above, but rather the intention is that additions and

modifications to what was expressly described herein are also included within the scope of the invention. Moreover, it is to be understood that the features of the various aspects described herein are not mutually exclusive and can exist in various combinations and permutations, even if such combinations or permutations were not made express herein, without departing from the spirit and scope of the invention. In fact, variations, modifications, and other implementations of what was described herein will occur to those of ordinary skill in the art without departing from the spirit and the scope of the invention. As such, the invention is not to be defined only by the preceding illustrative description.

Accordingly, what is claimed is:

1. An apparatus for practicing techniques for combat sports, the apparatus comprising:
  - a grappling upright, which further comprises an upright first side and an upright second side which upright first side and upright second side are joined to each other with a grappling top angle between the upright first side and the upright second side; and which further comprises a grappling first side vertical section which is at a grappling lower angle of approximately 0°-15° to the upright first side, and a grappling second side vertical section which is at a grappling lower angle of approximately 0°-15° relative to the upright second side, with an internal horizontal span between the grappling first side vertical section and the grappling second side vertical section; and which grappling upright comprises a front of the apparatus;
  - a floor piece having outside edges;
  - a first horizontal brace;
  - a plurality of horizontal brace supports;
  - a plurality of upright-horizontal braces, which brace the grappling upright to the floor piece;
  - wherein the front of the apparatus is distant from the front of the first horizontal brace by a distance referred to as a first horizontal brace setback.
2. The apparatus of claim 1, in which the grappling top angle is approximately 150° to 170°.
3. The apparatus of claim 1, in which an internal vertical span of the apparatus is approximately 36" to 60".
4. The apparatus of claim 1, in which the upright first side of the grappling upright is covered with a first upright pad and the upright second side of the grappling upright is covered with a second upright pad.
5. The apparatus of claim 1, in which the floor piece comprises a first horizontal tube and a second horizontal tube, which are below the grappling upright and approximately perpendicular to the grappling upright.
6. The apparatus of claim 5, in which the first horizontal tube and the second horizontal tube are formed from a single piece of material continuous with the grappling upright.
7. The apparatus of claim 1, in which the grappling upright may be reversibly attached to and detached from the floor piece through an interlocking mechanism.
8. The apparatus of claim 1, in which the floor piece comprises a continuous solid sheet made of or coated with low-friction material.
9. The apparatus of claim 1, in which the floor piece comprises one or more horizontal lateral bends.
10. The apparatus of claim 1, in which the floor piece comprises one or more upright bends.
11. The apparatus of claim 1, in which the floor piece further comprises a first horizontal runner and a second horizontal runner, which comprise or are coated with a low-friction material.

12. The apparatus of claim 1, in which the floor piece further comprises a solid sheet of low-friction material between the outside edges of the floor piece.

13. The apparatus of claim 1, in which a first horizontal runner and a second horizontal runner are separate from the floor piece, and are attached to the floor piece with a plurality of first horizontal runner supports and a plurality of second horizontal runner supports. 5

14. The apparatus of claim 1, in which the first horizontal brace setback is approximately 8" to 24". 10

15. The apparatus of claim 1, in which the first horizontal brace can support additional mass.

16. The apparatus of claim 1, in which the internal horizontal span is approximately 8" to 24".

17. The apparatus of claim 1, in which the floor piece 15 further comprises a plurality of assistant-user-footblocks.
